UNITED STATES PATENT OFFICE

ULRIK I. T. BLOMBERG, OF ENSKEDE-STOCKHOLM, SWEDEN, ASSIGNOR TO DITTO, INCORPORATED, OF CHICAGO, ILLINOIS, A CORPORATION OF WEST VIRGINIA

STORAGE RACK

Application filed July 28, 1928. Serial No. 296,026.

This invention relates to storage racks and in particular to that type of rack adapted for the storage of heavy elongated objects.

An object of the invention is to provide a rack for such service affording a maximum capacity and requiring a minimum of occupied floor space.

Another object is to make the contents of the rack easily available and a further object is to produce a rack, having the above qualifications, of light and permanent construction and reasonable cost.

In the accompanying drawings, I have illustrated one adaptation of my invention applied to the storage of gelatin hectograph duplicating rolls so that it may be readily comprehended, but it is to be understood that it is merely illustrative and that the scope of the invention is by no means confined thereto.

In these drawings, which form a part of this application—

Figure 1 is an elevation of my invention.

Figure 2 is a sectional view taken along the plane indicated by the arrows 2—2 of Figure 1.

Figure 3 is a sectional view taken along the plane indicated by the arrows 3—3 of Figure 1, while—

Figure 4 is a section through the supporting hub and spindle on the plane indicated by arrows 4—4 of Figure 3.

Referring to the figures, it will be seen that the rack assembly rests upon a four-legged foundation 1. These legs are T-section, branching from a central hub, and terminate in radial bosses, the under sides of which are formed to the friction bearing surfaces 2. One of these is adjustable to compensate for variation on floor level as shown at 3. The central vertical spindle 4 is force fitted into the cast hub 5. Clamped to this spindle, and resting upon the upper surface of the central bearing hub is the cam ring 6 fixed in position by a set screw. Said cam

ring 6 may also be termed a cam member or a cam collar. The upper surface 7 of this cam ring is shaped to four elevations and four depressions alternating each other in equal radial disposition. Riding upon this cam ring is a follower member 8, the lower sur-

face of which is formed to register to the upper surface of the cam ring 6. A freely rotatable supporting collar 13 surrounds the upper section of the central spindle 4.

The racks proper are composed of the four vertical box members 14, which are of triangular cross-section and formed of crimped sheet metal. These vertical triangular members are supported and positioned by the lower radial arms 9, fastened to the cam follower member, the upper radial arms 12, attached to the upper supporting collar 13, and the inclined diagonal compression struts 11. These triangular members in turn carry the multiple roll supporting brackets 15. Each of these brackets consists of the vertical web section 16, the inclined supporting surface 17 and the back stop lug 18. They are fastened to the sides of the aforementioned triangular members by spot welding or other suitable means. It should be noted that the inner ends of the brackets are slightly lower than the outer.

As will be clear from inspection of the drawings, the radial arms 12—12 are made up of metal strips. The radial arms 9—9 may be substantially identical with the radial arms 12—12 and a description of the arms 12—12 will suffice for the arms 9—9 as well. According to the illustration embodying the present invention in which four radial arms 12—12 are provided, said arms are formed from four strips 12a—12a which are identical with each other. Each of said strips 12a—12a takes the form of a truncated V the base of which is secured by bolts or other preferred securing means to the collar 13. The legs of said strips 12a—12a diverge at an angle slightly greater than ninety degrees, the legs of adjacent strips 12a—12a converging outwardly to form the arms 12—12.

The radial arms 9—9 adjacent to the bottom of the rack comprise the strips 9a—9a similar to the strips 12a—12a immediately above referred to.

As noted above, each of the box members 14 is of triangular cross-section. According to the illustrated embodiment of the present invention, each of said box members comprises three sheets of metal indicated by the

numerals 14a, 14b and 14c. The vertical edges of said metal members 14b and 14c may be secured to the metal member 14a by any preferred means. According to the disclosure of the present invention said metal members 14b and 14c are secured to the metal member 14a by means of crimping. It will be clear that any other preferred means may be employed for securing the members 14a, 14b and 14c together as a unit, or, if preferred, said members may be integral with one another. The box structure provides rigidity in the rack without involving excess weight.

The vertical edges of the members 14b and 14c, distinct from the member 14a, are provided with the flanges 14d-14d which flanges extend toward the axis of the spindle 4 and are disposed between the outer extremities of adjacent legs of the strips 12a-12a adjacent to the top of the leg and the strips 9a-9a adjacent to the bottom of the leg.

The gelatin hectograph duplicating rolls 19 are provided with the projecting spindle ends 20 which are supported by these brackets. When placed thereon, they will tend to gravitate towards the axis of the rack until stopped by the lugs 18.

The rack illustrated is designed to carry twenty-four of such rolls.

30 The rack assembly is rotatable about the central spindle 4, but such movement is checked at each 90° by the interaction of the cam ring 6 and the follower member 8. The slope of the cam faces and the interacting followers is such that if the rack assembly is given a reasonable initial movement, it will swing into, but stop on, the next 90° position, as above stated.

40 The upper end of the spindle 4 engages with the socket bracket 21, and supports a shelf assembly 22 with storage for stationery, ink, or similar supplies. The shelf arrangement may be varied at will or a table or other attachment substituted.

45 Having described my invention, what I claim as new and desire to secure by Letters Patent of the United States is:

50 1. In a device substantially as described, the combination of a supporting base having multiple radial legs, a leveling means attached to one of said legs, a central vertical spindle, a cam collar clamped to the lower section of said spindle and adjacent to said supporting base, a cam follower member freely movable on said central spindle and riding on said cam collar, a rotatable collar on the upper end of said spindle, a roll carrying structure composed of vertical hollow sheet metal members of triangular cross-section, 55 provided with roll supporting brackets; means for carrying said vertical members composed of upper radial arms attached to said upper movable collar and lower radial arms attached to said cam follower and inclined struts attached to said cam follower.

and to the outer ends of said upper radial arms.

2. In a device of the character described, in combination, a supporting base, a vertical spindle carried thereby, a cam member rigidly disposed relative to said spindle, a cam follower rotatable relative to said spindle and adapted to ride upon said cam member, a collar rotatable relative to said spindle spaced vertically above said cam follower, a rack structure supported by said spindle and rigidly connected to said cam follower and to said collar, said rack structure comprising a plurality of elongated box members circumferentially disposed about said spindle in parallel relation to said spindle, said box members comprising triangular figures, opposed faces of adjacent boxes being parallel with one another, radial arm members connecting said box members with said follower and said collar, and struts connecting the upper extremities of said box members with said cam follower.

3. In a rotatable storage rack, in combination, a vertical supporting spindle, a cam member rigid with said spindle, a cam follower riding upon said cam member, said cam follower being adapted to rotate relative to said spindle, a collar adapted to rotate about said spindle above said cam follower, radial arms rigidly connected to said cam follower and to said collar, vertical box members secured to said radial arms at their outer extremities, said box members comprising triangular figures, opposed faces of adjacent boxes being parallel with one another, and struts connecting the upper extremities of said box members with said cam follower.

4. In a rotatable storage rack, in combination, a vertical supporting spindle, a cam member rigid with said spindle, a cam follower riding upon said cam member, said cam follower being adapted to rotate relative to said spindle, a collar adapted to rotate about said spindle above said cam follower, radial arms rigidly connected to said cam follower and to said collar, vertical box members secured to said radial arms at their outer extremities and struts connecting the upper extremities of said box members with said cam follower, said box members comprising triangular figures, opposed faces of adjacent boxes being parallel with each other.

5. In a storage rack, in combination, a supporting spindle, a rack structure carried thereby, said rack structure including a pair of spaced collars rotatably disposed relative to said spindle, a plurality of radial arms secured to each of said collars and vertical box members secured to the extremities of said arms, said box members comprising triangular figures, opposed faces of adjacent boxes being parallel, said opposed faces of adjacent box members being provided with cooperating supporting brackets, inclined struts each

5 having one extremity thereof connected to one of said collars and the other extremity thereof connected to an extremity of one of said radial arms, and means for yieldably holding said rack structure in successive circumferential positions relative to said spindle.

6. In a storage rack, in combination, a vertical spindle, a pair of collars encircling said 10 spindle at regions spaced along said spindle, a plurality of radial arms connected to each of said collars, said radial arms connected to each of said collars being made up of metal strips of truncated V-shaped conformation, the bases of said V-shaped conformations being secured to their corresponding collars, adjacent legs of adjacent strips converging toward one another away from said spindle, and elongated box members disposed 15 parallel with said spindle, said box members being secured to extremities of said radial arms.

7. In a storage rack, in combination, a vertical spindle, a pair of collars encircling said 20 spindle at regions spaced along said spindle, a plurality of radial arms connected to each of said collars, said radial arms connected to each of said collars being made up of metal strips of truncated V-shaped conformation, the bases of said V-shaped conformations being secured to their corresponding collars, adjacent legs of adjacent strips converging toward one another away from said spindle, elongated box members disposed parallel 25 with said spindle, said box members being secured to extremities of said radial arms, and inclined struts each having one extremity thereof connected to one of said collars and the other extremity thereof connected to 30 an extremity of one of said radial arms.

Signed at Chicago, Illinois, this 19th day of July, 1928.

ULRIK I. T. BLOMBERG.
